(57) **CLAIM**

The ornamental design for a pressure regulator.

DESCRIPTION

FIG. 1 is a perspective view from below showing my new design;

FIG. 2 is a side elevational view from one side of the pressure regulator shown in FIG. 1;

FIG. 3 is a side elevational view from the other side of the pressure regulator shown in FIG. 1;

FIG. 4 is a perspective view from above of the pressure regulator shown in FIG. 1;

FIG. 5 is a top plan view of the pressure regulator shown in FIG. 1;

FIG. 6 is a bottom plan view of the pressure regulator shown in FIG. 1;

FIG. 7 is a perspective view from below from another angle of the pressure regulator shown in FIG. 1;

FIG. 8 is a perspective view from above from another angle of the pressure regulator shown in FIG. 1; and,

FIG. 9 is an exploded perspective view of the design of FIGS. 1-8.
